Oliver C. Wood, of Euphrata, N.Y.

Letters Patent.

The schedules referred to in these Letters Patent and making part of the same containing a description in the words of the said Oliver C. Wood himself of his improvement in the machine for raising Water for propelling machinery and for other purposes.

Be it known that I, Oliver C. Wood, of Euphrata in the County of Montgomery and State of New York, have invented a new and useful improvement in the machine for raising Water for propelling machinery, and for other purposes which is described as follows:

This machine consists of a shaft around which is constructed a double threaded screw, one outside of the screw, a tight drum, or barrel, forming continuous spiral treads from one end of the shaft to the other similar to the common Archimedean screw having apertures at the lower end, on the side, for introducing water and apertures at the upper end for discharging it.

The shaft is placed in a current or in tide water inclined at an angle of about 20, 30, or 45 degrees turning in,wards inside, end of its ends in suitable dogs or bows contoured to receive them by means of the current or tide acting on wings of a triangular form fixed in a permanent manner near the lower end of the outside barrel or screw, the the shaft turns at yathis in the water at its lower end and conveys it by its rotary motion along the spiral treads to the top where it is enlarged into a reservoir. From this reservoir a portion of it may be conducted to a outlet, or undershot wheel for propelling machinery.

What I claim as my invention and which I desire to secure by Letters Patent, consists in the form of the wings or fins and the manner of securing them to the outside of the cylindrical drum or barrel when open by the current or tide, in the
